UNITED STATES PATENT OFFICE.

HANS J. BENTSON, OF WINTHROP HARBOR, ILLINOIS, ASSIGNOR TO FREDERICK C. AUSTIN, OF CHICAGO, ILLINOIS.

TRENCHING-MACHINE.

1,327,418.

Specification of Letters Patent. Patented Jan. 6, 1920.

Application filed September 15, 1916. Serial No. 120,271.

To all whom it may concern:

Be it known that I, HANS J. BENTSON, a citizen of the United States of America, and resident of Winthrop Harbor, Lake county, 5 Illinois, have invented a certain new and useful Improvement in Trenching-Machines, of which the following is a specification.

My invention relates to excavating machines of that kind in which a movable or 10 traveling body is provided at its rear end with digging apparatus for cutting a trench as the machine moves slowly forward.

The object of my invention is to provide an improved construction and arrangement 15 whereby practically the entire machine, except the under-frame and traction devices, is movable bodily sidewise, during the operation of the digging apparatus, so that a trench may be formed which is wider than 20 the digging apparatus, thus making it possible to form a wide trench without the necessity of widening the excavator.

It is also an object to provide certain 25 details and features of construction and combinations tending to increase the general efficiency and desirability of a trenching machine of this particular character.

To the foregoing and other useful ends, my invention consists in matters hereinafter 30 set forth and claimed.

In the accompanying drawings:—

Figure 1 is a side elevation of an excavator embodying the principles of my invention.

Fig. 2 is a plan view of a portion of said 35 machine.

Fig. 3 is an enlarged side elevation of those portions of the machine shown in Fig. 2, with certain parts shown broken away for convenience of illustration.

40 Fig. 4 is a rear elevation of said machine, showing a cross-section of the trench, and illustrating how the machine cuts a trench which is wider than the digging apparatus.

Fig. 5 is an enlarged plan view of certain 45 parts of the machine.

Fig. 6 is a cross-section on line 6—6 in Fig. 5.

Fig. 7 is a cross-section on line 7—7 in Fig. 5.

50 Fig. 8 is a cross-section on line 8—8 in Fig. 5.

Fig. 9 is a detail sectional view showing the clutch mechanism for controlling the intermittent forward movement of the excavator.

Fig. 10 is a side elevation of the mechanism shown in Fig. 9, being an enlarged section on line 10—10 in Fig. 5.

Fig. 11 is a cross-section on line 11—11 in Fig. 4.

Fig. 12 is a diagrammatic view showing the manner in which the earth is removed by successive forward and sidewise cuts to form the trench.

Fig. 13 shows a modification of the mechanism for automatically controlling the intermittent forward movement of the machine.

As thus illustrated, my invention comprises an under-frame A mounted on caterpillars B, or other suitable traction devices, 70 and provided with front wheels C, whereby the machine may move forward in the direction desired for the trench. The body D is disposed immediately above the under-frame A, and is provided with longitudinally disposed shafts E and F having rollers or wheels 1 which engage the transverse tracks 2 on the under-frame, it being understood that said shafts are mounted in suitable bearings on said body. With this construction the entire machine, except the under-frame and the traction devices, is movable bodily sidewise. The body D is provided with a frame d provided with bearings of any suitable character for supporting the rear transverse shaft 3 which supports the upper end of the digging beam G, the latter being of any suitable or desired form, and provided with endless chains g having digging buckets 4 for cutting the 90 trench. These chains g are supported on sprockets or other rotary members mounted on the shaft 3 and at the lower end of the digging beam. In this way, the beam G is adapted to swing up and down about the 95 horizontal and transverse axis provided by the shaft 3, and any suitable means, such as the cable 5 and sheaves 6 and 7, can be employed for hoisting the beam out of the ground. The sheave 6 is suitably mounted 100 on the digging beam, and the sheave 7 is suitably mounted on the frame d, and the hoisting cable 5 can be operated by any suitable means. A rack-bar H extends transversely of the trench, cross-wise of the digging beam G, so that the latter is adapted to slide laterally thereon, the said bar and beam being suitably connected for this purpose. The ends of said bar are provided 105 with means for engaging the sides of the 110

trench. A shaft 8 extends up and down the beam G, being mounted in suitable bearings thereon, and is provided at its lower end with a pinion 9 for engaging said rack-bar, whereby rotation of this shaft will shift the beam and buckets laterally on said rack-bar, from one side of the trench to the other, in the desired manner. For this purpose, the shaft F is provided with a rear telescoping extension f, and with a universal joint 10, whereby this extension can swing up and down with the digging beam. The rear end of this extension f is provided with a bevel pinion 11 for engaging the bevel gear 12, which latter in turn engages the bevel pinion 13 on the upper end of the shaft 8, so that the rotation of the shaft F is in this way communicated to the shaft 8 when the body D is shifted sidewise in either direction. The belt 14 is suitably driven by an engine e or other motive power, carried on the body D, and rotates the pulley 15 on the transverse shaft 16, which latter is provided with a sprocket connection 17 with the shaft 3, whereby the latter is driven to operate the buckets. This shaft 3 is provided with loose bevel pinions 19 and 20 for engaging the bevel gear 21 on the upper end of the vertically disposed shaft 22, which latter is mounted in suitable bearings on the framework d, in a manner that will be readily understood. The clutch member 23 on the shaft 3 is movable into and out of engagement with the bevel pinions 19 and 20, thereby to reverse the rotation of the vertical shaft 22, in a manner that will be readily understood. The lower portion of this shaft 22 is provided with a worm 24 which engages a worm-wheel 25 on the shaft F, thus causing the latter to turn one way or the other, depending upon the position of the clutch member 23, which latter thus controls the shifting of the excavator sidewise. In order that the sidewise movement of the excavator may be positive and forcible in character, the shafts E and F are provided with pinions 26 for engaging the racks 27 which extend parallel with the tracks 2 on the under-frame. The traction devices B are driven by sprocket chains b from the square shaft 28 which is mounted to rotate in suitable bearings on the under-frame A, and which is driven by a sprocket connection 29 with the transverse shaft 30 mounted in suitable bearings on the body D which is movable sidewise. Said body D is provided with rigid portions 31 at each side of the sprocket for the connection 29, so that the latter slides sidewise on the shaft 28, when the body is shifted from one side to the other. The shaft 30 is driven by a gear connection 32 with the shaft 33, which latter is mounted in suitable bearings on the body D, and this shaft 33 is in turn driven by a gear connection 34 with the adjacent shaft

35 which is also mounted in suitable bearings on the body. A sprocket chain 36 connects the shaft 35 with the shaft 37, which latter is mounted in bearings on the body directly below the shaft 16, and power is transmitted from the shaft 16 to the shaft 37 through a gear connection 38 of any suitable character. This gear connection 38 has a clutch 39 on the shaft 37, and by opening and closing this clutch the power-transmitting connection between the engine and the traction devices B is opened and closed. 70

The machine thus far described can be used for making a trench, in the manner indicated in Fig. 12, by simply controlling the clutches 23 and 39 in any suitable or desired manner, so that the machine will first move ahead the desired distance, while the buckets 4 are operating, thus producing one of the narrow cuts X, which is the same 85 in width as the buckets, and which would be the width of the trench if no means were provided for shifting the digging apparatus sidewise. However, as soon as the cut X is made, then the clutch 39 is opened to 90 prevent further forward movement of the machine, and the clutch 23 is shifted into engagement with one of the bevel pinions 19 or 20, so that the worm 24 is rotated one way or the other, thus causing rotation of 95 the shafts E and F to shift the machine sidewise on the tracks 2, in a manner that will be readily understood. This lateral shifting of the machine will produce one of the cuts Y, and is made by the gradual sidewise movement of the buckets while they are being operated up and down on the digging beam. As soon as the buckets have reached the limit of this sidewise cut, which is the side of the wide trench, the clutch 23 is then moved to a middle position between the two bevel pinions 19 and 20, thus stopping the sidewise movement. The clutch 39 is then again closed, with the result that another forward cut X is then 100 made at the opposite side of the wide trench. In this way, the operation proceeds by first a narrow forward cut at one side of the wide trench, then a sidewise cut toward the other side of the trench, and then a forward cut at this side of the trench, followed by a sidewise cut toward the side of the trench where the first forward cut was made, and so on until the wide trench is finished. 105

As a matter of further and special improvement, however, the clutches 23 and 39 are automatically controlled as follows: The clutch 23 has a pivoted shifting lever 40 which extends downward to engage the cam-plate 41. This cam-plate is mounted 110 to slide in longitudinal guides 42 on the body D, and said plate is provided with two oppositely formed cams 43 and 44 for engaging the roller 45 on the lower portion of said lever, whereby the latter is rocked 115

from one side to the other about its axis 46, when the plate is pulled forward. Said plate is connected by a link 47 with an arm 48 of the rock-shaft 49, which latter is arranged transversely of the machine and mounted in suitable bearings on the body D, as shown more clearly in Fig. 7, and is provided with an upstanding arm 50 at its other end. The sprocket chain 36 is provided with a laterally projecting pin 51 arranged in position to engage the arm 50 when this pin travels toward the forward end of the machine, so that the shaft 49 will be rocked to pull the plate 41 forward and thereby shift the clutch 23 into engagement with either one or the other of the bevel pinions 19 and 20, depending upon which of the two cams 43 and 44 is brought into engagement with the roller 45, in a manner that will be readily understood. The lower end of the lever 40 slides on a rod 52 which is mounted transversely on the under-frame of the machine, and which is provided with stops 53, whereby the lever 40 is operated whenever the body of the machine reaches the limit of its sidewise movement in either direction, so that the clutch member 23 is automatically shifted to middle or neutral position between the two bevel pinions 19 and 20, thus stopping the rotation of the shaft 22, and thereby leaving the machine in its laterally shifted position. The clutch 39 is operated by a bellcrank 54 which has a roller 55 for engaging the cam-track 56, the latter having its ends deflected forward to form the cams 57, this cam-track being simply a bent channel-iron. At about the same time that the body D of the machine reaches the limit of its sidewise movement, so that the lower end-portion of the lever 40 is operated by one of the stops 53, the roller 55 encounters one of the cams 57, whereby the clutch 39 is closed to cause the rotation of the shaft 37, thus causing the rotation of the square shaft 28 by which the traction devices 50 are operated to move the machine forward. To do this the stops 53 must, of course, be adjusted in proper position on the rod 52, so that they will engage the lever 40 at the proper times and in a manner to produce the mode of operation stated. This forward movement of the machine continues, it will be seen, until the pin 51, previously described, strikes the lever-arm 50 on the rock-shaft 49, thereby moving the plate 41 forward and causing a shifting of the lever 40, with a consequent engagement of the clutch member 23 with one of the bevel pinions 19 or 20, so that the rotation of the shaft 22 is started for the purpose of rotating the shafts E and F to shift the body D toward the other side of the machine, causing the buckets to make a sidewise cut away from the forward cut which was made while the traction devices

B were in operation. The forward movement ceases, of course, immediately after the beginning of the return sidewise motion and as soon as the clutch 39 is opened again by disengagement of the roller 55 from the cam 57. The shaft 49 has a downwardly extending arm 58 provided with a spring 59 arranged to operate said shaft in a direction to push the plate 41 backward as soon as the arm 50 is released by the pin 51, so that said plate will always stand in position to be pulled forward to operate the lever 40 each time the machine reaches the limit of one of its forward movements. The arrangement and adjustment of the parts must be such, obviously, that when lever 40 is operated a distance by a stop 53, thus stopping the lateral motion of the body, the operation leaves the roller 45 just a little to the other side of the point formed by the cams 43 and 44, so that when plate 41 is pulled forward the roller 45 will engage the proper cam to carry the lever the balance of the distance necessary to reverse the clutch 23 in the manner explained. 90

From the foregoing, it will be seen that with the construction shown and described a comparatively narrow trenching machine can be used for making a very wide trench, by a series of forward and sidewise cuts, as shown in Fig. 12, so that it will not be necessary to widen the machine objectionably in order to produce a wide trench. The back-and-forth sidewise movements of the machine alternate with periods or intervals of rest, and the forward movements occur during these intervals of cessation of the lateral movements. 95

As shown in Fig. 13, a bar 60 extends transversely of the machine, being mounted on the under-frame A in any suitable manner. This bar is provided with cams 61 which are adjustable longitudinally thereof, and which take the place of the cams 57 previously described. With this construction, and by adjusting these cams 61 toward and away from each other, and with the stops 53 located in different positions on the rod 52 (see dotted positions in Fig. 5) the width of the trench can be varied to suit the requirements in any particular case. Adjustment of the cams 61 will, of course, require readjustment of the stops 53, as the lever 40 will travel sidewise more or less according to the width desired for the trench. 110

The forward movements of the excavator alternate with the sidewise movements thereof, and there is practically no sidewise movement while the excavator is moving ahead, nor any forward movement while the excavating apparatus is moving sidewise. Thus, each sidewise cut is straight across, and of less length than the width of the ditch, and these transverse slices, as they may be called, overlap each other at the middle of the 120

130

trench, (see Fig. 12), and these slices Y are distinct and separate from the forward cuts X, the sidewise and forward movements of the excavator being distinct and independent of each other. With this construction and method of operation, a single machine is capable of making trenches of different widths, and the digging apparatus can be of a width to make a very narrow trench, if desired. Thus, a larger and broader field of utility is insured for the machine, as it is capable of making either a narrow or a wide trench; and, although the digging beam G may be quite narrow, still the means provided for pushing on the sides of the trench (see Figs. 4 and 11) insures against breakage and straining of the beam, as the lower portion of the beam itself is propelled sidewise at the same speed that its upper portion is moved sidewise in either direction.

What I claim as my invention is:—

1. An excavating machine comprising an under-frame having traction devices, a body mounted on said under-frame to move bodily sidewise thereon, digging apparatus carried at the rear end of said body, means for operating said digging apparatus while said devices are in operation to move the excavator slowly forward, thereby to produce a forward cut in the ground, mechanism to shift said body laterally during the operation of said apparatus and while said devices are stationary to produce a sidewise cut away from said forward cut, thereby to form a trench the width of which is equal to the width of a forward cut plus the length of the sidewise cut, said apparatus comprising a beam arranged to swing up and down about a horizontal and transverse axis at the upper end thereof, and means in the trench to propel the beam sidewise in unison with the sidewise movement of said body.
2. An excavating machine comprising an under-frame having traction devices, a body mounted on said under-frame to move bodily sidewise thereon, digging apparatus carried at the rear end of said body, means for operating said digging apparatus while said devices are in operation to move the excavator slowly forward, thereby to produce a forward cut in the ground, mechanism to shift said body laterally during the operation of said apparatus and while said devices are stationary to produce a sidewise cut away from said forward cut, thereby to form a trench the width of which is equal to the width of a forward cut plus the length of the sidewise cut, said apparatus comprising an endless series of buckets which travel upward in loading position to produce the successive cuts which form the trench, and means in the trench to propel said buckets sidewise in unison with the sidewise movement of said body.

3. An excavating machine comprising an under-frame having traction devices, a body mounted on said under-frame to move bodily sidewise thereon, digging apparatus carried at the rear end of said body, means for operating said digging apparatus while said devices are in operation to move the excavator slowly forward, thereby to produce a forward cut in the ground, and mechanism to shift said body laterally during the operation of said apparatus and while said devices are stationary to produce a sidewise cut away from said forward cut, thereby to form a trench the width of which is equal to the width of a forward cut plus the length of the sidewise cut, said apparatus comprising a digging beam which is equipped with an endless series of digging buckets and arranged to extend downward into the trench, a rack-bar associated with said beam to extend transversely thereof and engage the opposite sides of the trench, a shaft on said beam, a pinion on the lower end of said shaft to engage said rack-bar, and means for connecting said shaft with said mechanism to propel said beam sidewise in unison with the sidewise movement of said body.

4. An excavating machine comprising an under-frame having traction devices, a digging apparatus mounted on said under-frame, so that a trench will be cut in rear of said under-frame when said devices are operated to move the entire machine forward, means including mechanism for pushing on the sides of the trench for shifting said apparatus back and forth laterally thereof to widen the trench, means for causing intervals of rest between said back-and-forth lateral movements of said apparatus, and means for automatically causing predetermined forward movements of the entire machine during said intervals of rest.

5. An excavating machine comprising an under-frame having traction devices, a body mounted on said under-frame to move bodily sidewise thereon, digging apparatus carried at the rear end of said body, means for operating said digging apparatus in the ground while said body is stationary on said under-frame and while said devices are in operation to move the excavator slowly forward in a direction parallel with the trench, thereby to produce a forward cut by horizontal movement of said digging apparatus bodily in the ground at one side of the trench, while said body remains stationary on the under frame and mechanism to shift said body laterally in a direction at right angles to the trench during the operation of said apparatus in the ground and while said devices and under-frame are stationary to produce a sidewise cut by horizontal movement of said digging apparatus bodily away from said forward cut and by move-

- ment of the digging apparatus laterally thereof to the other side of the trench, thereby to form a trench the width of which is equal to the width of a forward cut plus 5 the length of the sidewise cut having means for stopping said lateral movement while the machine is moving forward.
6. An excavating machine as specified in claim 5, said mechanism comprising transverse racks on said under-frame and pinions on said body to engage said racks.
7. An excavating machine as specified in claim 5, having means to automatically start and stop the operation of said mechanism, and automatic means to start and stop 15 the operation of said traction devices, so that the forward cuts alternate automatically with the lateral cuts.
8. An excavating machine as specified in 20 claim 5, having means to automatically start and stop the operation of said devices, so that no forward movement occurs while the body is moving sidewise, and automatic means to start and stop the operation of 25 said mechanism, so that lateral movement is automatically prevented while the machine is moving forward.
9. An excavating machine as specified in 30 claim 5, having automatic means to start and stop the operation of said traction devices, and automatic means to start and stop the operation of said mechanism, so that said body is automatically held stationary on said under-frame while the 35 excavator is moving forward, and whereby the excavator is automatically controlled, while said apparatus is at work in the ground, to produce the successive forward and sidewise cuts which form the trench.
- 40 10. An excavating machine as specified in claim 5, and adjustable means to control said mechanism at will to vary the width of the trench.
11. An excavating machine comprising an 45 under-frame having traction devices, a digging apparatus mounted on said under-frame, so that a trench will be cut in rear of said under-frame by horizontal movement of said apparatus bodily when said devices are 50 operated to move the entire machine forward, mechanism to shift said apparatus bodily and horizontally and laterally thereof in one direction transversely of the trench while the machine is standing still 55 and while said apparatus is operating in the ground thereby to make a straight transverse cut in the ground, means to automatically stop said lateral movement, means to automatically start the operation of 60 said devices to move the machine forward a distance after the lateral movement has ceased and while said apparatus is still operating in the ground, whereby the lateral movement is interrupted at about the time the forward 65 movement is started, means to
- automatically reverse said mechanism to return said apparatus laterally in the opposite direction, said forward horizontal movement being automatically stopped at about the time the return sidewise movement is started, so that no lateral movement occurs while the machine is making a straight forward cut in the ground, and provisions to automatically stop return lateral movement and again start the forward movement 70 when said apparatus reaches the limit of said return movement, whereby the excavation progresses in the line of direction of the ditch by longitudinal movements of said apparatus automatically alternating with transverse movements thereof.
12. An excavating machine comprising an under-frame having traction devices, a digging apparatus mounted on said under-frame, so that a trench will be cut in rear of 85 said under-frame by horizontal movement of said apparatus bodily when said devices are operated to move the entire machine forward, mechanism to shift said apparatus bodily and horizontally and laterally thereof 90 in one direction transversely of the trench while the machine is standing still, thereby to make a straight transverse cut in the ground, means including a clutch controlled by the lateral shifting of said apparatus to 95 automatically stop said lateral movement thereof, means including a clutch controlled by the lateral shifting of said apparatus to automatically start the operation of said devices to move the machine forward a distance 100 after the lateral movement has ceased, and while said apparatus is still operating in the ground, so that the lateral movement is interrupted at about the time the forward movement is started, means for controlling 105 said first mentioned clutch to automatically reverse said mechanism to return said apparatus laterally in the opposite direction, said forward horizontal movement being automatically stopped by said last mentioned 110 clutch at about the time the return lateral movement is started, and provisions to automatically stop return lateral movement and again start the forward movement when said apparatus reaches the limit of said return movement, so that no lateral movement 115 occurs while the machine is making a straight forward cut in the ground, whereby the excavator progresses in the line of direction of the ditch by longitudinal movements 120 of said apparatus automatically alternating with transverse movements thereof.
13. An excavating machine comprising an under-frame having traction devices, a digging apparatus mounted on said under-frame, so that a trench will be cut in rear of said under-frame, by horizontal movement of said apparatus bodily when said devices are operated to move the entire machine forward, mechanism including means 125
- 130

to push against the side of the trench to shift said apparatus bodily and horizontally and laterally thereof in one direction transversely of the trench while the machine is standing still, means to automatically stop said lateral movement, means to automatically start the operation of said devices to move the machine forward a distance after the lateral movement has ceased, and while 5 said apparatus is still operating in the ground, so that the lateral movement is interrupted at about the time the forward movement is started, means to automatically reverse said mechanism to return said apparatus laterally in the opposite direction, said forward horizontal movement being automatically stopped at about the time the return lateral movement is started, and provisions to automatically stop said return 10 lateral movement and again start the forward movement when said apparatus reaches the limit of said return movement, whereby the excavation progresses in the line of direction of the ditch by longitudinal movements of said apparatus automatically alternating with transverse movements thereof.

14. An excavating machine comprising an under-frame having traction devices, a digging apparatus mounted on said under-frame, so that a trench will be cut in rear of said under-frame by horizontal movement of said apparatus bodily when said devices are operated to move the entire machine forward, mechanism to shift said apparatus bodily and horizontally and laterally thereof in one direction transversely of the trench while the machine is standing still, a power plant to operate the entire machine and mounted to shift laterally with 15 said apparatus, means including a clutch controlled by the lateral shifting of said apparatus to automatically stop said lateral movement thereof, means including a clutch controlled by the lateral shifting of said apparatus to automatically start the operation of said devices to move the machine forward a distance after the lateral movement has ceased, and while said apparatus is still operating in the ground, so that the lateral movement is interrupted at about the time the forward movement is started, means to automatically reverse said mechanism to return said apparatus laterally in the opposite direction, said forward horizontal movement being automatically stopped at about the time the return lateral movement is started, and provisions to control said clutches and thereby automatically stop said return lateral movement and again start 20 the forward movement when said apparatus reaches the limit of said return movement, whereby the excavation progresses in the line of direction of the ditch by longitudinal

movements of said apparatus automatically alternating with transverse movements thereof.

15. An excavating machine comprising an under-frame having traction devices, a digging apparatus mounted on said under-frame, so that a trench will be cut in rear of said under-frame by horizontal movement of said apparatus bodily when said devices are operated to move the entire machine forward, means for shifting said apparatus back and forth horizontally and bodily and laterally thereof to widen the trench, said apparatus being adapted to make a straight transverse cut in the ground when moved laterally, means for causing intervals of rest between said back-and-forth lateral movements of said apparatus, and means for automatically causing predetermined horizontal forward movements of the entire machine and thereby forming straight forward cuts in the ground during said intervals of rest.

16. An excavating machine comprising an under-frame having traction devices, a digging apparatus mounted on said under-frame, so that a trench will be cut in rear of said under-frame when said devices are operated to move the entire machine forward, means for shifting said apparatus back and forth horizontally and bodily and laterally thereof to widen the trench, said apparatus being adapted to make a straight transverse cut in the ground when moved laterally, means for automatically causing intervals of rest between said back-and-forth lateral movements of said apparatus, and means for automatically causing predetermined horizontal forward movements of the entire machine and thereby forming straight forward cuts in the ground during said intervals of rest.

17. An excavating machine comprising an under-frame having traction devices, a digging apparatus mounted on said under-frame, so that a trench will be cut in rear of said under-frame when said devices are operated to move the entire machine forward, means for shifting said apparatus back and forth horizontally and bodily and laterally thereof to widen the trench, a power plant connected to operate the entire machine and mounted to shift laterally with said apparatus, means for causing intervals of rest between said back-and-forth lateral movements of said apparatus, and means for automatically causing predetermined horizontal forward movements of the entire machine during said intervals of rest.

Signed by me at Chicago, Illinois, this 6th day of September, 1916.

HANS J. BENTSON.
